US0D1013175S

(12) **United States Design Patent** (10) Patent No.: **US D1,013,175 S**
(45) Date of Patent: ** Jan. 30, 2024

(54) **MEDICAL IMAGING DEVICE**

(71) Applicant: **Siemens Healthcare GmbH**, Erlangen (DE)

(72) Inventors: **Stefanie Gügel-Wild**, Langensendelbach (DE); **Thomas Kunz**, Fürth (DE)

(73) Assignee: **Siemens Healthcare GmbH**, Erlangen (DE)

(**) Term: **15 Years**

(21) Appl. No.: **29/849,513**

(22) Filed: **Aug. 11, 2022**

(30) **Foreign Application Priority Data**

Feb. 15, 2022 (EM) 008860324-0001

(51) **LOC (14) Cl.** **24-01**

(52) **U.S. Cl.**

USPC **D24/158**

(58) **Field of Classification Search**

USPC D24/107, 158-161, 185, 186, 187, 183, D24/184

CPC A61B 6/03; A61B 6/035; A61B 6/037; A61B 6/0407; A61B 6/0487; A61B 5/05; A61B 5/055

See application file for complete search history.

(57) **CLAIM**

The ornamental design for a medical imaging device, as shown and described.

DESCRIPTION

FIG. 1 is a front elevational view of a medical imaging device showing our new design;

FIG. 2 is a back elevational view thereof;

FIG. 3 is a top plan view thereof;

FIG. 4 is a bottom plan view thereof;

FIG. 5 is a left-side elevational view thereof;

FIG. 6 is a right-side elevational view thereof; and,

FIG. 7 is a top, front, left-hand side perspective view thereof.

The broken lines shown in the drawings represent portions of the medical imaging device that form no part of the claimed design.

1 Claim, 7 Drawing Sheets
